UNITED STATES PATENT OFFICE.

CHARLES F. GOFORTH, OF LEMOORE, CALIFORNIA.

AUTOMATIC OILER.

Application filed October 26, 1926. Serial No. 144,839.

This invention relates to internal combustion engines and aims to provide novel means for increasing the efficiency of the engine by supplying moisture to the fuel 5 entering the intake manifold of the engine.

Another object of the invention is to provide means for leading gases which usually collect in the crank casing, to the intake manifold, novel means being provided for 10 superheating the gases and moisture prior to its passage to the intake manifold.

A still further object of the invention is to provide a device of this character which may be readily and easily installed on internal 15 combustion engines, eliminating the necessity of making alterations in the construction to position the same.

With the foregoing and other objects in view which will appear as the description 20 proceeds, the invention resides in the combination and arrangement of parts and in the details of construction hereinafter described and claimed, it being understood that changes in the precise embodiment of the 25 invention herein disclosed, may be made within the scope of what is claimed, without departing from the spirit of the invention.

Referring to the drawing:

Figure 1 is a side elevational view illustrating an attachment constructed in accordance with the invention as installed on an internal combustion engine.

Figure 2 is a longitudinal sectional view through a portion of the attachment.

Figure 3 is a sectional view taken on line 35 3-3 of Figure 1.

Figure 4 is a sectional view taken on line 4-4, Figure 2.

Figure 5 is a sectional view taken on line 40 5-5 of Figure 2.

Referring to the drawing in detail, the reference character 5 designates the breather pipe of an internal combustion engine to which the attachment forming the essence of this invention is connected, the attachment including a flexible pipe 6 shown as having its lower end positioned within the breather pipe 5.

Positioned within the upper end of the 50 flexible pipe section 6 is a perforated disk 7 which is slightly bulged as shown by Figure 2 of the drawing, to the end that the gas and fumes from the crank case will be directed upwardly, the condensates dropping downwardly onto the disk 8, which is disposed at the lower end of the flexible pipe

section 6 and at a point adjacent to the breather pipe.

This disk 8 is of a diameter less than the diameter of the pipe section 6 so that there 60 will be a space between the periphery of the disk and the flexible pipe 6, to the end that the gases must contact with the disk in their upward passage from where the gases are forced laterally through the passageway between the disk and flexible pipe.

The reference character 9 designates a pipe that has connection with the pipe 6 at its lower end, the upper end of the pipe 9 being connected with the elbow 10, which in turn is formed with an upwardly curved end wall 11 spaced from the upper wall of the elbow 10 to accommodate one end of the pipe 12.

The reference character 13 designates a pipe that has its upper end extended into the upper portion of the radiator 14 forming a part of the cooling system of the internal combustion engine, the pipe 13 extending downwardly where it has communication with the tank 15 to the end that steam or vapor generated at the upper portion of the radiator may be carried downwardly to the tank 15 where condensates will be trapped.

Communicating with the tank 15 is a pipe 85 16 that has its upper end extended into the elbow where it is supplied with a valve 17, the valve including a ball 18 that normally seats to obstruct the passage of steam or vapor unless the engine is operating to consume the same.

The valve member 17 may be closed by means of the threaded member 26 operating through a threaded opening in the elbow 10, the lower portion of the threaded member 26 being formed with a transversely disposed cut out portion 27 to allow the passage of vapor or steam from the valve member, the quantity of vapor or steam being regulated by turning the member 26 to uncover 95 greater or less portions of the cut out portion 27.

Positioned within the pipe 12 is a screening member 25 disposed adjacent to the entrance end of the pipe 12 so that the vapors 105 and steam will be thoroughly screened separating the condensates therefrom, prior to its passage through the pipe 12.

Connected with one end of the pipe 12 is a pipe 23 which has its lower end connected with the air intake opening of the carburetor, which in the present showing is indi-

cated at 24, with the result that the gases passing from the breather pipe will be mixed with the steam or vapor from the radiator and with the incoming air to increase the efficiency of the engine.

From the foregoing it will be seen that inasmuch as the pipe 12 is supported directly over the exhaust manifold of the internal combustion engine, fuel will be thoroughly heated insuring against condensates passing to the carburetor.

I claim:

In combination with the radiator and breather pipe of an internal combustion engine, a pipe communicating with the breather pipe to carry off gases therefrom, a heating pipe adapted to be positioned over the exhaust pipe of an internal combustion

engine and having a passageway heated by the heat from the exhaust pipe, a tank communicating with the radiator to receive water therefrom, a pipe leading from the tank and extending into the pipe leading from the breather pipe and having a threaded extremity a valve member having a slotted lower portion fitted in the pipe and adapted to be adjusted to vary the length of the slotted portion to regulate the quantity of vapors passing from the tank to the pipe, and means for establishing communication between the heating pipe and carburetor of the engine.

In testimony that I claim the foregoing as my own, I have hereto affixed my signature.

CHARLES F. GOFORTH.
